US0D1055267S

(12) United States Design Patent (10) Patent No.: US D1,055,267 S
Martell et al. (45) Date of Patent:  Dec. 24, 2024

(54) COMBINED CEILING FAN MOTOR
HOUSING AND LIGHT KIT

(71) Applicant: Hunter Fan Company, Memphis, TN (US)

(72) Inventors: Timothy Martell, Minneapolis, MN (US); Ryan Lee Eiffert, Memphis, TN (US)

(73) Assignee: Hunter Fan Company, Memphis, TN (US)

() Term: 15 Years

(21) Appl. No.: 29/826,320

(22) Filed: Feb. 11, 2022

CLAIM

The ornamental design for a combined ceiling fan motor housing and light kit as shown and described.

DESCRIPTION

FIG. 1 is a bottom perspective view of a combined ceiling fan motor housing and light kit, shown in the environment of a ceiling fan, showing my new design;

FIG. 2 is a bottom perspective view thereof, with the ceiling fan environment removed;

FIG. 3 is a top view thereof;

FIG. 4 is a bottom view thereof; and,

FIG. 5 is a side view thereof.

Portions of the combined ceiling fan motor housing and light kit, and the ceiling fan environment shown in broken lines form no part of the claimed design.

1 Claim, 5 Drawing Sheets
